UNITED STATES PATENT OFFICE.

CHARLES E. BLACKBURN, OF BROOKLYN, NEW YORK.

SIPHONIC FLUSHING APPARATUS.

1,157,667.

Specification of Letters Patent.

Patented Oct. 26, 1915.

Application filed March 1, 1913. Serial No. 751,533.

To all whom it may concern:

Be it known that I, CHARLES E. BLACKBURN, a citizen of England, residing at Brooklyn, in the county of Kings and State of New York, have invented certain new and useful Improvements in Siphonic Flushing Apparatus, of which the following is a specification.

This invention relates to improvements in water outlet valves for flushing tanks and as its principal object contemplates the provision of a siphon controlled water outlet and means for operating the siphon from the exterior of the tank.

An object of equal importance is to equip the siphons with such means as will effectively eliminate the rattling noise ordinarily observed in outlet valves of this type.

A yet further object is to construct the siphon in such manner that the siphonic action of the device will cease when the water level in the tank has fallen to a predetermined point.

The above and additional objects are accomplished by such means as are illustrated in their preferred embodiment in the accompanying drawings, described in the following specification and then more particularly pointed out in the claim which is appended hereto and forms a part of this application.

With reference to the drawings, wherein, I have illustrated the preferred embodiment of my invention as it is reduced to practice, and throughout the several views of which, similar reference numerals designate corresponding parts: Figure 1 is a vertical section of a flush of customary structure equipped with the siphon. Fig. 2 is an enlarged view showing a vertical section of the siphon. Fig. 3 is a section on the line 3—3. Fig. 4 is a detail view of the attaching ring employed in effecting the mounting of one of the siphon tubes.

Proceeding now to the description of the drawings, the numeral 1 indicates a flushing tank of the usual type within which is mounted a siphon outlet valve designated as an entirety in Fig. 1 by the numeral 2. The siphon includes a vertically mounted stationary tube 3, a vertically movable tube 4 and a sealing tube 5, the latter member being mounted in fixed relation to the tube 4 and adapted for corresponding vertical sliding movement therewith. The tube 3 is open at each end and intermediate its

length is provided with the circumferentially spaced, longitudinally extending openings 6, provided for a purpose to be hereinafter disclosed. A discharge pipe 7 is mounted in a suitable orifice formed in the bottom wall 8 of the tank and is provided with an annular outwardly extending shoulder 9 formed adjacent the upper end and is further provided with a circular recess wherein is seated the lower end of the tube 3. A washer 10 is mounted on the top of the member 7 and encircles the tube 3. This washer may be made of any suitable pliable material such as leather, fiber or rubber. A washer 11 of similar nature is disposed between the shoulder 9 and the wall 8 to insure the sealing of the joint. A lock nut 12 is mounted in screw threaded engagement with the pipe 7 and bears against the under face of the wall 8, thus holding the member 7 securely in the desired position. The tube 4 incases the tube 3 and is in turn incased by the sealing cylinder 5, the outer wall of the member 4 being spaced from the inner wall of the member 5. The member 4 carries a lead washer 13 at its lower end and at its upper end is exteriorly screw threaded to receive the projecting cap 14. This latter member is essentially a metallic cap carrying a diametrically positioned bail member 15 which is formed with a centrally positioned internally screw threaded orifice 16 provided to receive the screw threaded connecting rod 17. A lock nut 18 is screw threaded on the member 17 and acts to hold the bail member 15 in rigid relation to the top 19 of the member 5, thus maintaining the tube 4 in spaced relation to the inner wall of the tube 5. A lever 20 pivotally mounted as at 21 and provided with an operating cable 22 is pivotally connected to the member 17 as at 23.

The construction and arrangement of parts of the invention being thus disclosed, I now pass to the description of the operation of the device.

Presuming the tank to be filled with water as indicated in Fig. 1 and the tubes 4 and 5 in the position indicated in dotted lines in Fig. 2, it will be seen that a pull exerted upon the lever will result in the upward movement of the sealing cylinder 5 and the tube 4. When the tube 4 has reached the position illustrated in Fig. 2, it is apparent that water will rush into the tube 3 through

the openings 6. Immediately after the band 12 is released, the lead band 12 will by reason of its weight operate to return the members 4 and 5 to their initial position. When the movable tubes have resumed the position indicated in dotted lines in Fig. 2, it is apparent that the openings 6 will be sealed, thus preventing water from entering into the tubes. However, at the movement of the final sealing of the openings 6, there will be a quantity of water in the tube 3 and as this water exhausts from the tube 3 a partial vacuum will be created, thus starting the siphonic action of my device. The opening 6 being closed, the water issues from the tank by siphonic action as indicated by the arrows in Fig. 2, until the water falls below the lower end of the tube 3.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction,

proportion and arrangement of parts may be resorted to, when required, as defined in the appended claim.

What is claimed is:

In a flush tank siphonic outlet valve mechanism, a fixed tubular outlet open at its upper and lower ends projecting into and a relatively considerable distance above the bottom of the tank and having outlet openings considerably above the bottom of the tank, a tube telescoping said fixed tube to have a fluid-tight fit therearound to open and close the outlet, and a sealing tube of enlarged diameter with respect to and fixed to said telescopic tube and having its lower margin substantially horizontally aligned with that of the telescoping tube to initiate and gradually increase siphonic action during descent of the sealing and telescoping tubes subsequent to closure of the outlet in the fixed tube by said telescoping tube.

In testimony whereof I affix my signature in presence of two witnesses.

CHARLES E. BLACKBURN.
